(57) **CLAIM**

The ornamental design for a foot file, as shown and described.

DESCRIPTION

FIG. 1 is a perspective view of an embodiment of a foot file. FIG. 2 is a side view of an embodiment of a foot file. FIG. 3 is a front view of an embodiment of a foot file. FIG. 4 is a back view of an embodiment of a foot file. FIG. 5 is a top view of an embodiment of a foot file; and, FIG. 6 is a bottom view of an embodiment of a foot file. The broken lines illustrate portions of the foot file and form no part of the claimed design.
